Primary Examiner — Ian F Whitmore(74) Attorney, Agent, or Firm — Plumsea Law Group, LLC(57) CLAIM

The ornamental design for a display screen with icon, as shown and described.

DESCRIPTION

The sole FIGURE is a front view of a display screen with icon showing the new design.

The broken lines of uneven length show the display screen and form no part of the claimed design.

1 Claim, 1 Drawing Sheet(56)
